BENJAMIN KOTKOVSKY, OF NEW YORK, N. Y., ASSIGNOR TO RAPID BUTTON ATTACHING MACHINE CO., OF NEW YORK, N. Y., A CORPORATION OF NEW YORK.

BUTTON MAGAZINE AND FEEDING DEVICE.

1,145,774.

Specification of Letters Patent.

Patented July 6, 1915.

Original application filed April 14, 1914, Serial No. 831,746. Divided and this application filed July 24, 1914. Serial No. 852,901.

To all whom it may concern:

Be it known that I, BENJAMIN KOTKOVSKY, a subject of the Czar of Russia, and a resident of the city of New York, borough 5 of Brooklyn, in the county of Kings and State of New York, have invented a new and Improved Button Magazine and Feeding Device, of which the following is a full, clear, and exact description.

10 This invention relates to button magazine and feeding devices especially adapted for use in connection with a staple forming and attaching machine, such as that disclosed in my application for Letters Patent, 15 Serial Number 831,746, filed April 14, 1914, and of which application the present one is a division. However, there are certain features of the invention which are not limited to machines of the character referred to, but 20 are susceptible to more general use.

The general objects of the invention are to improve the construction and operation of machines of the character referred to so as to be thoroughly reliable and efficient in 25 use, automatic in its various operations, and so designed as to be adapted for use with buttons of different sizes.

30 A specific object of the invention is the provision of a new form of button-feeding chute or raceway provided with means for effecting the discharge of buttons one at a time therefrom to the staple-forming and attaching mechanism, such means and chute being so designed as to be suitable for but- 35 tons of different sizes.

Another specific object is to so mount the chute that it can be moved out of operative position and tilted to such an inclination that the buttons will flow back automatically into the hopper from which the chute 40 is fed, whereby the chute can be emptied to permit its use with buttons of a different size from the buttons in the hopper, the hopper being capable of being adjusted to a position of inoperativeness, so that buttons can be fed to the chute by hand.

Another object is the employment in connection with an oscillatory button hopper, of movable button pick-up means therein 50 and so designed as to pick up one or more buttons and deliver them to the feed chute of the machine in a predetermined position,

all other buttons not in such predetermined position being dropped back in the hopper so that clogging of the feeding system is 55 prevented.

With such objects in view, and others which will appear as the description proceeds, the invention comprises various novel features of construction and arrangement of 60 parts which will be set forth with particularity in the following description and claims appended hereto.

In the accompanying drawings, which illustrate one embodiment of the invention, 65 and wherein similar characters of reference indicate corresponding parts in all the views, Figure 1 is a side view of the machine with the parts in initial position, the button hopper being shown in section; Fig. 1^a is a 70 detail sectional view on line 1^a—1^a, Fig. 1; Fig. 2 is a view similar to Fig. 1, showing the hopper in lowered or idle position, as when a feed chute is being fed by hand with a style of button different from that in the 75 hopper; Fig. 3 is a view showing the staple bender and driving elements at the end of their working strokes and a button attached to a shoe or other article by the staple there- 80 of being clenched and another button ready to be delivered to the staple mechanism; Fig. 4 is a fragmentary plan view of the button feeding mechanism, the cover of the hopper being open; Fig. 5 is a side view of the button pick-up means in the hopper for 85 selecting the buttons and feeding them to the button chute; Figs. 6 and 7 are sectional views, with the parts in different positions, to show the manner of picking up buttons and dislodging those buttons which are in 90 improper position to enter the chute, Figs. 8 and 9 are face views respectively of the two plates forming the button pick-up de- 95 vice in the hopper.

Referring to the drawings, 1 designates 95 the table or shelf of the machine, which is formed with a hub 2 that is suitably fastened to the upper end of a hollow standard or column 3 provided at its lower end with a suitable tripod or base frame (not shown), 100 and extending through this column is an operating rod 4 that has its lower end connected with a depressible spring-raised treadle (not shown) whereby power is applied to

the machine for operating the various instrumentalities thereof. On the table 1 is a frame A that supports an inclined chute B that receives buttons from a hopper C in which is a button pick-up means D, which oscillates in a vertical plane in the hopper C, so that buttons can be taken out by the device and delivered to the chute B. At the lower end of the chute is a combined staple-forming and driving mechanism E to which buttons are fed from the chute by an ejector F and a star wheel G.

The feed chute or raceway B comprises a pair of vertically disposed triangular plates 5 and 6 which are secured together in spaced relation, so that the inclined upper edges 7 will form a raceway for the buttons to slide down, and by spacing the plates 5 and 6 apart a longitudinal groove is provided in this raceway for the shanks or eyes of the buttons. A guard 8 extends longitudinally of the raceway and is spaced above the edges 7 so that it is impossible for the buttons to be thrown out of the raceway, such guard being fastened to the plates of the chute by brackets 9. At the lower end of the chute and forming extensions of the edges 7 of the plates of the chute are springs 10 which support the buttons as they are being conducted from the chute to the staple-forming mechanism, the springs being yielding so as to accommodate buttons of different sizes. Reciprocating over this yielding extension of the chute formed by the springs 10 is the ejector F, which has a bifurcated lower extremity 11 which is adapted to engage slightly above the center of the lowermost button in the chute so as to eject such button as the ejector moves downwardly from the position shown in Fig. 3. This ejector is slidably mounted on the lower end of the button guard 8, and on this guard is a stop or gate element 12 in the form of a spring extending over the buttons and having its lower end free so as to yieldingly hold the buttons in the chute. On the guard is a pin 13 arranged with its lower end bearing on the spring 12 and the upper end of the pin is adapted to be engaged by a cam surface 14 on the ejector, so that as the latter is moved to eject a button the cam 14 will press the spring downwardly so that its free extremity will be in the path of the descending next button as the lowermost button is being forced out by the ejector F. This tensioning of the spring by the pin 13 does not take place until after the lowermost button has passed out of gripping relation to the spring or gate 12. The reciprocation of the ejector is performed by a toothed segment 15 pivoted at 16 on extension lugs 17 of the guard 8, and the teeth of the segment mesh with rack teeth 18 on the ejector. The segmental gear 15 is provided with an arm 19 formed with parallel lugs 20 between which

engages a pin 21 on a reciprocating actuating element or link 22. This link, as shown in Fig. 2, is hingedly connected at 23 with the upper end of a swinging arm 24 which is fulcrumed at 25 on the side of the frame A. This arm 24 is provided with a pin 26 which extends into the frame A through a slot 27, the inner end of this pin 26 being engaged by a reciprocating element forming part of the staple-forming mechanism, so that the button ejector will be operated to eject a button in timed relation to the said mechanism.

The button feeder or star wheel G is located between the button ejector and staple-forming mechanism and is mounted on a shaft 28 journaled in a bearing 29, and on this shaft is a ratchet wheel 30 with which engages a pawl 31 pivoted at 32 on an arm 33 loosely mounted on the star wheel shaft 28. The pawl-carrying arm 33 is connected by the pivot screw 34 with the link 22, as clearly shown in Fig. 3, so that as the link moves back and forth it will oscillate the pawl-carrying arm and move the pawl 31 into engagement with the successive teeth of the ratchet wheel 30 to move the same step by step, and consequently move the star button feeding wheel in the same manner. A spring-pressed pawl 35, Fig. 2, also engages the ratchet wheel so as to prevent back travel thereof. The star wheel G moves one step with each ejecting movement of the ejector F, and the teeth or arms 36 of the star wheel successively engage buttons to deliver them to the staple-forming mechanism. The button holder H, which holds the button in position to receive a staple wire or blank, is an approximately rectangular frame having its side members 37 spaced apart with their rear ends fulcrumed on the screw pivot 38 which passes through recesses 39^a in the plates 5 and 6 of the button chute B, the screw being fastened in a bearing 40, Fig. 3. The lower portion of the star wheel lies between the side members 37 of the button holder, and the ejector F moves downwardly between these members in ejecting a button. The under side of the holder H near its free end is provided with an approximately semi-circular recess 41 which is adapted to receive the head of a button when the latter is in staple-receiving position, as shown by the dotted lines in Fig. 3, whereby the button is held properly in place. The star wheel G moves the button from the ejector toward the button-receiving recess 41. The head of the button during this movement from the ejector first slides on the resilient members or springs 10 and thereafter on the top surface of the staple bender 42 and staple driver 43. The holder H is provided with a button retainer or guide 44 which embodies a pair of rearwardly and upwardly 130

curved fingers 45 extending along opposite sides of the bottom portion of the star wheel, this button retainer being pivoted at 46 and yieldingly pressed downwardly by a spring 47, so as to lie in the path of the button that is fed by the star wheel. The button as it feeds under the guide 44 and holder H will lift the latter so that it will control the wire-feeding mechanism, but as this latter is not a part of the present invention it is unnecessary to show or describe it. To assist the star wheel in moving the button to staple-receiving position the staple driver is provided with a button shank-engaging element 48 arranged in the slot 49 which is provided in the driver for allowing the shanks of the buttons to pass into staple-receiving position. This element 48 is adapted to yield to allow the shanks of the buttons to pass along by the star wheel, and as soon as the shanks pass the tip 49' of the element 48, the latter is thrown upwardly by a spring 50 acting on this element, and consequently as the driver moves forwardly to drive a staple, the element 48 will at the same time carry the next button into position to be received by the holder H, so that when the parts of the staple forming the driving mechanism return to normal position, the button will be ready to receive a staple wire from the wire-feeding mechanism. Immediately after receiving the wire the bender comes into play to form the staple, and thereafter the driver acts to drive the staple into the fabric and attach the button. The feeding movement of the star wheel occurs as the driver is nearing the end of its backward stroke and causes the button to assume a position where the shank will be in front of the element 48, so that with the next stroke of the driver a button will be moved to staple-receiving position, while at the same time a button-supplied staple will be attached to the shoe or other article.

To permit access to the button-feeding means, as well as to the staple-forming mechanism, the feed chute B is pivotally mounted on a pivot 51 on the rear upper corner of the frame A, and consequently the chute can be tilted to the dotted-line position, Fig. 2. A catch 52 is arranged to lock the chute in normal position. This catch is mounted on a pivot stud 53 and has a pin 54 which passes through a bearing bracket 55 on which the chute is pivoted, and this pin is adapted to engage with the chute to hold the same in normal position. By pressing the handle 56 of the latch 52 against the tension of the spring 57, Fig. 4, the latch can be released so that the chute can be moved to the dotted-line position, Fig. 2. In throwing out the chute in this manner the pin 21 on the link 22 disengages the ejector which is carried by the chute

while the link 22 remains in position. This throwing back of the chute B is also made use of to empty the chute of its buttons, as the buttons in the chute will slide back into the hopper C, so that the chute can be used for the hand feeding of buttons of a different size from the buttons in the hopper, it being understood that the hopper will, during the hand feeding, remain in the full-line position, Fig. 2, so that buttons can be placed in the upper end of the chute without the hopper interfering.

To prevent the buttons in the chute from emptying out as the chute is being thrown back, an automatic gate or stop device 58, Fig. 3, is employed to move into engagement with the button in the lower end of the chute and prevent the button from sliding out. This device 58 is pivoted at 59, and its button-engaging tip 60 is normally retracted out of the path of the buttons in the chute by the extremity 61 engaging an abutment 62 which is stationary with respect to the table or frame of the machine. A spring 63 carried by the chute presses on the gate device 58 so that when the chute begins to move out of its normal position the tip 60 of the gate device will move into the feed groove of the chute or raceway and engage the shank of the button in the bottom of the chute. It will thus be seen that the gate device 58 is automatically closed and opened with the movement of the chute from or to operative position.

The hopper C is a metal or other box having a cover 64. The front wall 65 of the hopper has an opening 66 which is adapted to align with the chute B, so that buttons can pass out of the opening into the chute. The bottom 67 slopes downwardly from both sides, and in the center is provided with a slot 68 through which the button pick-up device D works up and down. The button pick-up device comprises a pair of vertically sliding plates 69 and 70. The upper edges 71 of the plates are beveled inwardly so as to better pick up the buttons in the hopper, and these plates are spaced apart to provide a longitudinal groove 72 between them to accommodate the shanks or eyes of the buttons while the heads of the latter rest on the upper edges 71 of the plates, and these plates when fully raised are in alignment with the chute, so that the buttons can flow by gravity down the plates and into the chute through the opening in the front wall of the hopper.

The pick-up plates 69 and 70 are actuated respectively by levers 69^a and 70^a connected by a horizontal shaft 71 journaled in the upper rear corner of the frame A. These levers have on their upper rear ends pins 69^b and 70^b movable in slots 72 and 73 on the plates 69 and 70, respectively, the said slots being of different configurations and so dis-

posed that as the levers 69^a and 70^a are oscillated the plates will move up and down in the hopper, but at differential rates, so that at a mid point in the travel the plates will 5 occupy the relative position shown in Fig. 7, and any button in improper position for feeding into the chute will be dislodged. When the plates are in their lowermost position they have their upper edges 71 opposite 10 each other, and when the plates are in their uppermost position this alignment also occurs, as shown in Fig. 6. To assist in dislodging those buttons which are not in position for feeding into the chute from the 15 pick-up device, the latter is provided with a kick-off element 74 in the form of a plate arranged in the outer face of the plate 70 and mounted to swing upwardly on a center 75, where the kick-off device is pivotally connected with the plate 70. This plate projects upwardly upon the top edge 71 of the plate 70 as the pick-up device moves, as shown in Fig. 7, and thereby dislodges buttons which do not have their shanks entered 20 in the slot 72, whereby such buttons are kicked off. Between the plates 69 and 70 is 25 a gate element 76 which is swung from the pivot 75 and is connected by a link 77 with a lever 78 swinging on a fulcrum 79 carried by the plate 70. On this lever 78 is a pin 80 which engages in a slot 81 in the plate 69, whereby the differential movement of the 30 plates will cause the free end of the gate element 76 to move upwardly to a position where it will hold the buttons from sliding 35 downwardly as the pick-up device D moves upwardly toward discharge position, and as its full discharge position is reached the gate element 76 is swung downwardly so as to be 40 out of the path of the buttons as they slide down the inclined top edges 71 of the pick-up plates 69, 70. The kick-off plate 74 has a projection 82 which forms a stop or gate element to prevent buttons from feeding out 45 of the pick-up device prematurely, but this lug is moved downwardly below the level of the top edge of the plate 70 when the pick-up device is fully raised and ready to discharge the buttons into the chute.

50 Another button kick-off device 70^a, Figs. 5, 6 and 7, is employed to dislodge buttons improperly positioned on the plate 69. This device is disposed between the plates 69 and 70 with its top edge below the top edge 71 55 of plate 70, and it is secured to the latter by a pin 70^a or other means. Due to the differential movement of the plates 69 and 70 it will be at an intermediate point in the upward movement of the button pick-up means 60 D, that the device 70^a will project above the top edge 71 of the plate 69, so that the buttons that have their shanks disposed between the device 70^a and plate 70 will be retained while other buttons on the plate 69 will be

dislodged. The kick-off device 74 moves up 65 and down with the gate element 76. Any suitable means may be used to connect these parts together, such as pins 76^a and 76^b, Figs. 5, 6 and 7.

The hopper C is adapted to have an up 70 and down oscillatory movement, and for this purpose it is provided with forwardly-extending arms 83 which are disposed at opposite sides of the chute B and are pivoted thereto by a horizontal pivot 84 which 75 also serves as a pivot for the forwardly-extending arms 69^c and 70^c of the pick-up plates 69 and 70, the arms of the said latter plates being disposed between the plates forming the button chute. The hopper is 80 adapted to drop by its own weight after the pick-up plates have moved to their lowermost position, and is adapted to be raised by the button pick-up device as the same moves upwardly, and for this latter purpose the plate 69 has a projection 85 on which the bottom of the hopper rests as the pick-up device D is moved upwardly by the levers 69^a and 70^a. A trip lever 86 is mounted on the frame A and swings on a pivot 87. 85 The upper end of this trip lever or catch has a notch 88 in which engages a projection 89 on the arm 83 of the hopper C, as shown in Fig. 1, and on the lower end of the trip lever is a projection 90 that is located in 90 the path of a projection 91 on the lever 69^a, so that as the said lever tilts during the downward movement of the button pick-up device D, the trip lever will be actuated so as to release the hopper and allow the same to drop, whereby the buttons in the hopper are agitated, and more effectively lodge on the pick-up device. A spring 92 is coiled 95 around the fulcrum 88 of the trip lever 86 and automatically returns the latter to a position where it will engage the projection 89 of the hopper when the latter is raised, so as to thereby support the hopper in raised position until it is again tripped. The lever 69^a for the button pick-up device is 100 connected to a link 93 which is connected at 94 with an arm 95 secured to the shaft 96 of the lever J. This arm 95 is loose on the shaft 96 and is adapted to be clutched there- 105 to when the buttons are to be fed automatically to the staple-forming and attaching mechanism. For clutching the parts together the shaft 96 has a disk 97 provided with a notch 98, and a catch 99 pivoted on the lever 95 is adapted to be engaged in the notch 98 of the disk 97, shown in Fig. 1, but when the catch 99 is released, as shown in Fig. 2, the hopper will be in lowered or 110 inoperative position, so that buttons can be fed to the chute by hand while the rest of the machine will operate as usual, with the exception of the button pick-up device and the hopper, 115

120

125

Having thus described my invention, I claim as new and desire to secure by Letters Patent:—

1. In a button attaching machine a feed chute, a reciprocatory ejector mounted at the discharge end of the chute for discharging the lowermost button, a spring forming a gate element for holding a series of buttons in the chute by engaging the lowermost button, and means actuated by the ejector during the ejecting stroke for moving the gate element into the path of the succeeding button as the lowermost button is being ejected.

15 2. In a machine of the class described a button feeding chute, a spring extending over the buttons and yieldingly engaging the lowermost button, an ejector, and means movable simultaneously with the ejector for actuating and placing the spring under tension during the ejecting of the lowermost button, to cause the spring to move into the path of the succeeding button and retain the same and the rest of the buttons in the 25 chute.

3. In a machine of the class described a button feeding chute, a hopper for delivering buttons thereto, and a vertically reciprocating pick-up device in the hopper and comprising differentially movable plates for picking up one or more buttons off each reciprocation and delivering them to the chute in a definite position, said device having means to kick off all buttons other than those 35 in such definite position.

4. In a machine of the class described a button feeding chute, a hopper at the upper end thereof, and button pick-up means movable to and from a point alining with the chute for supplying buttons to the latter, said means including a plurality of plates having their upper edges shaped to hold buttons in the position they occupy in sliding down the chute, and means for 40 imparting differential movement to the plates to dislodge all buttons picked up thereby in improper position for feeding.

5. In a machine of the class described a button feeding chute, a hopper at the upper 50 end thereof, and button pick-up means movable to and from a point alining with the chute for supplying buttons to the latter, said means including a plurality of plates having their upper edges shaped to hold buttons in the position they occupy in sliding down the chute, means for imparting differential movement to the plates to dislodge all buttons picked up thereby in improper position for feeding, and a gate or 55 stop device movable with the plates to prevent the movement of buttons into the chute until the plates are in feeding alinement with the chute.

6. In a machine of the class described a button feeding chute, a hopper mounted to

oscillate in a vertical plane at the upper end of the chute, and button pick-up means within the hopper for feeding buttons to the chute, said means including plates having their upper ends shaped to form a button-receiving slot, means for moving the plates upwardly and downwardly and producing differential movement for dislodging buttons in improper position to feed to the chute, and a stop or gate device carried by the plates for preventing movement of the buttons from the plates until the latter are in feeding alinement with the chute.

7. In a machine of the class described a button feeding chute, a button hopper, and means for picking up buttons in the hopper and supplying them to the chute, said means including a pair of plates having their upper edges shaped and disposed to form a groove to receive the shanks of the buttons, members carried by and movably mounted on the plates to dislodge all buttons resting thereon without the shanks being in the said groove, and means for actuating the plates to move the button-receiving edges into and out of feeding alinement with the chute and imparting differential movement to the plates in passing from receiving to discharge position for dislodging buttons in improper position for feeding.

8. In a machine of the class described a button feeding chute, a button hopper, and means for picking up buttons in the hopper and supplying them to the chute, said means including a pair of plates having their upper edges shaped and disposed to form a groove to receive the shanks of the buttons, members carried by and movably mounted on the plates to dislodge all buttons resting thereon without the shanks being in the said groove, means for actuating the plates to move the button-receiving edges into and out of feeding alinement with the chute and imparting differential movement to the plates in passing from receiving to discharge position for dislodging buttons in improper position for feeding, and a gate carried by the plates and movable by the differential movement thereof to retain the buttons on the plates until they are in position to slide from the plates into the chute.

9. In a machine of the class described a button-feeding chute, a button hopper, and means for picking up buttons in the hopper and supplying them to the chute, said means including a pair of plates having their upper edges shaped and disposed to form a groove to receive the shanks of the buttons, members carried by and movably mounted on the plates to dislodge all buttons resting thereon without the shanks being in the said groove, means for actuating the plates to move the button-receiving edges into and out of feeding alinement with the chute

and imparting differential movement to the plates in passing from receiving to discharge position for dislodging buttons in improper position for feeding, a gate carried by the plates and movable by the differential movement thereof to retain the buttons on the plates until they are in position to slide from the plates into the chute, a device for supporting the hopper as the plates move downwardly and adapted to be automatically tripped to permit the hopper to drop, and means on the plates for raising the hopper as the plates move upwardly.

10. In a machine of the class described 15 a button feeding chute, a hopper for delivering buttons thereto, and a vertically reciprocating pick-up device in the hopper for picking up one or more buttons on each reciprocation and delivering them to the chute 20 in a definite position, said device having means to kick off all buttons other than those in such definite position, said device comprising relatively movable plates shaped to provide a slot at their upper edges to receive 25 the shanks of the buttons.

11. In a machine of the class described a button feeding chute, a hopper for delivering buttons thereto, and a vertically reciprocating pick-up device in the hopper for 30 picking up one or more buttons on each reciprocation and delivering them to the chute in a definite position, said device having means to kick off all buttons other than those in such definite position, said device comprising plates movable up and down in the 35 hopper and differentially movable with respect to each other, the upper edges of the plates forming a longitudinal slot in its top disposed in line with the chute to receive 40 the shanks of the buttons, and the portions at either side of the slot being insufficient to support a button having its shank outside of the slot.

12. In a machine of the class described a 45 button feed chute, an ejector at the discharge end thereof, a support for the ejector, a spring on the support having a free end arranged to engage the lowermost button and form a yielding, normally open gate, a sliding 50 member on the support with one end impinging on the spring, and a cam on the ejector for engaging the member to move the spring into the path of a succeeding button as the lowermost button is being 55 ejected.

13. A button-feeding chute, an ejector for discharging buttons from the chute, a star-wheel for receiving the ejected buttons and conveying them therefrom, and actuating 60 means for the ejector and star wheel.

14. A button-feeding chute, an ejector for discharging buttons from the chute, a star wheel for receiving the ejected buttons and conveying them therefrom, and an actuating 65 means connected with the ejector and

star wheel for moving the same simultaneously.

15. A button-feeding chute, an ejector for discharging buttons from the chute, a star wheel for receiving the ejected buttons and conveying them therefrom, a ratchet means for turning the star wheel step by step, and a connection between said means and ejector for moving the latter every time the star wheel moves a step. 75

16. A button-feeding chute, an ejector for discharging buttons from the chute, a star wheel for receiving the ejected buttons and conveying them therefrom, a ratchet means for turning the star wheel step by step, an oscillatory member geared to the ejector for moving the same, and means connecting the member with the ratchet mechanism for moving the star wheel and ejector in synchronism. 80

17. A supporting frame, a star wheel for feeding buttons, a ratchet means for moving the star wheel step by step and including an oscillatory element, a feed chute on the frame, a reciprocatory button ejector carried by the feed chute, an oscillatory member carried by the feed chute and connected with the ejector for moving the same back and forth, an actuating arm mounted on the frame, a link connected with the arm and the said oscillatory element of the ratchet mechanism, and a connection between the link and operating member for the ejector, said connection including detachably engaged parts for permitting the chute to be moved from normal position while the ejector and operating member remain *in situ*. 95

18. In a button attaching machine a button supply chute, a button feeding element receiving buttons from the chute, an ejector at the discharge end of the chute and movable to deliver buttons one at a time to the feed element, and an actuating means for the feed element and ejector. 105

19. In a button attaching machine a supporting frame, a reciprocating part within the frame, a button feed chute, a feeding element receiving buttons from the chute, an ejector movable back and forth for delivering a button from the chute to the feeding element, operating connections between the element and ejector for effecting simultaneous movement thereof, said connections being disposed outside the frame, and means for actuating the said connections by the 115 said reciprocating part within the frame. 120

20. In a machine of the class described a feed chute for supplying buttons, a hopper for supplying buttons to the chute and mounted to move therewith when the chute 125 is moved from operative position for emptying backward into the hopper, a pivot on which the chute is tiltable, and means for normally holding the chute against tilting.

21. In a machine of the class described a 130

feed chute for supplying buttons, and an oscillatory hopper at the upper end of the chute and including button pick-up means disposed in and movable downwardly independently of and prior to the hopper and movable upwardly with the hopper for supplying buttons to the chute.

22. In a machine of the class described a chute for supplying buttons, an oscillatory hopper at the upper end of the chute, button pick-up means within the hopper for arranging buttons to feed into the chute, an actuator for the button pick-up means and serving to raise the hopper, and a latch device for holding the hopper raised as the actuator moves downwardly, and released finally by the actuator to permit the hopper to drop as the button pick-up means is in receiving position.

23. In a machine of the class described a chute for supplying buttons, an oscillatory hopper at the upper end of the chute, vertically reciprocating button pick-up means in the hopper, a swinging lever for actuating the pick-up means for raising the hopper, and a device adapted to be tripped by the lever during the latter part of its downward movement for releasing and permitting the hopper to drop.

24. In a machine having a button attaching mechanism, a button feed chute removably mounted with respect to the mechanism and pivoted on a horizontal axis, and a movable stop device mounted on the chute to retain the buttons therein when the chute is moved out of its operative position and adapted to be automatically released to permit buttons to feed when the chute is set in operative position.

25. In a machine having a mechanism for attaching buttons successively to an article,

a button feeding chute inclined downwardly to the mechanism and pivotally mounted on a horizontal axis to be moved out of feeding relation to the mechanism, and an automatically actuated stop or gate for preventing the discharge of buttons from the chute as the latter is moved from operative position.

26. In a machine having a mechanism for attaching buttons successively to an article, a button feeding chute inclined downwardly to the mechanism and pivotally mounted on a horizontal axis to be moved out of feeding relation to the mechanism, an automatically actuated stop or gate for preventing the discharge of buttons from the chute as the latter is moved from operative position, and a hopper arranged in coöperative relation with the chute for normally feeding buttons thereto and adapted to receive the buttons from the chute when the latter is moved out of operative position.

27. In a machine having a button attaching mechanism and actuating means therefor, a feed chute, an oscillatory button hopper, means in and movable on one stroke with and on the other stroke independently of the hopper for picking up buttons and supplying them to the chute, an operating element for moving both the hopper and said button pick-up means, and a clutch for connecting the said operating means with the actuating means of the button attaching mechanism.

In testimony whereof I have signed my name to this specification in presence of two subscribing witnesses.

BENJAMIN KOTKOVSKY.
